United States Patent

Des. 240,717
Patented July 27, 1976

240,717

CLOCK OR SIMILAR ARTICLE

Arthur M. Felske, Westport, Conn., assignor to
General Electric Company

Filed Mar. 10, 1975, Ser. No. 556,642

Term of patent 3½ years

Int. Cl. D10—01

U.S. Cl. D10—6

Fig. 1.

Fig. 2.

Fig. 4.

FIG. 1 is a right front perspective view of a clock or similar article showing my new design, it being understood that the inner dial portion's design is continuous;

FIG. 2 is a top plan view thereof;

FIG. 3 is a front elevational view thereof, it being understood that the inner dial portion's design is continuous; and

FIG. 4 is a right side elevational view thereof, the left side being substantially a mirror image thereto.

I claim:

The ornamental design for a clock or similar article, as shown, and described.
